UNITED STATES PATENT OFFICE.

EDGAR E. CROUCH, OF TOPEKA, KANSAS, ASSIGNOR OF ONE-HALF TO
J. M. KEITH, OF DES MOINES, IOWA.

PROCESS OF MOLDING ARTIFICIAL-STONE BLOCKS.

SPECIFICATION forming part of Letters Patent No. 790,481, dated May 23, 1905.

Application filed September 26, 1904. Serial No. 226,060.

To all whom it may concern:

Be it known that I, EDGAR E. CROUCH, a citizen of the United States of America, and a resident of Topeka, Shawnee county, Kansas, have invented a new and useful Process of Molding Artificial-Stone Blocks, of which the following is a specification.

The object of this invention is to provide an improved process of molding artificial-stone blocks without the use of wooden or metal pallets or carrying-plates.

My invention consists in the process of molding hereinafter set forth, pointed out in my claims, and illustrated by the accompanying drawings, in which—

Figures 1 to 5, inclusive, illustrate successive steps in my improved process.

In carrying out my improved process I employ a mold constructed, preferably, according to my invention set forth in an application for patent pending concurrently herewith and embodying side plates 10 11, end plates 12 13, pattern-plates 14, cores 15 16, and a bottom plate 17, carrying said cores. The mold is first positioned as shown in Fig. 1 and filled with composition 18, such as a mixture of sand and cement, or sand, cement, and gravel or broken stone, which composition is tamped in the mold and around the cores therein. A pallet 19 of sand is provided formed or constructed adjacent the mold. The pallet 19 has a plane upper face and may slope at its margins to the surface of the floor of ground on which

it is made. The sand pallet 19 preferably is dry and made by placing relatively fine sand over the space to be occupied thereby and smoothed, screeded, and leveled on its surface. The mold filled with tamped composition is inverted upon the pallet 19, as illustrated by Fig. 3, and the bottom 17 of said mold is tamped or stomped to loosen the cores in the composition and also to settle the mold in the sand pallet. The bottom plate 17 is then lifted away from the mold and carries with it the cores 15 16. The side plates, end plates, and pattern-plates of the

mold are then removed from the composition laterally, and the resultant artificial-stone block 20 is left standing on the sand pallet to 50 cure and dry. The dry sand pallet retains moisture in the block, and moisture evaporates from said block, thus providing for perfect and uniform curing and drying and hardening of the block.

Ordinarily great expense is involved in procuring wooden or metal pallets on which to dry and cure artificial-stone blocks, and such pallets retain moisture for a longer time in the block on account of their relatively 60 impervious condition. By my improved process I avoid the large expense for pallets, since the sand pallets may be broken up and replaced and re-formed indefinitely and repeatedly and have the further advantage 65 of assisting instead of retarding the curing process or operation on account of their porous and absorbent characteristics.

The sand pallets pack somewhat during the operation of placing and tamping or 70 stomping the mold on them, and consequently provide a firm and substantial base for the blocks.

I claim as my invention—

1. The process of molding artificial-stone 75 blocks, which process consists in forming a pallet of sand with a plane surface, tamping composition in a mold, inverting said mold on the plane surface of said pallet, and removing the mold from the composition contents thereof.

2. The process of molding artificial-stone blocks, which process consists in filling a mold with composition, forming a pallet of sand, inverting said mold on said sand pallet, 85 removing said mold from the composition contents thereof, and drying and curing said composition on said sand pallet.

Signed by me at Memphis, Tennessee, this 1st day of August, 1904.

EDGAR E. CROUCH.
